SANITARY CONTAINER

John S. Wright, Wichita, Kans.

Application April 24, 1934, Serial No. 722,657

3 Claims. (Cl. 220—36)

My invention relates to an improvement in sanitary containers. The object of my invention is to provide a sanitary container, the container proper of which is concealed within a housing to hide from view the contents of the container. Another object is to provide a sanitary container which may be sterilized. Another object is to provide a sanitary container having a housing and a cover therefor; with an opening having a closure therefor that can be opened by a foot pedal. Another object is to provide a container of the kind mentioned in which the container proper can be readily removed and replaced. Another object is to provide a container of the kind mentioned, which is simple and inexpensive to manufacture. Another object is to provide a sanitary container of the kind mentioned which is neat and clean in appearance. These and other objects will be more fully explained as this description progresses.

Now referring to the drawings, in which the same characters of reference designate the same part throughout the several figures.

Fig. 1 is a sectional view of my sanitary container. Fig. 2 is a sectional view of my sanitary container as seen from line II—II in Fig. 1. Fig. 3 is a plan view of my sanitary container. Fig. 4 is a plan view of my sanitary container having the top thereof removed. Fig. 5 is a plan view of my sanitary container having the top thereof and the container proper removed. Fig. 6 is a detail perspective view of the closing element for the opening in my sanitary container showing the closing element therefor. Fig. 7 is a modified form of Fig. 6. Fig. 8 is a detail perspective view of the foot pedal and associated parts for operating the parts shown in Figs. 6 and 7. Fig. 9 is an enlarged detail perspective view of the rear end of the foot pedal lever and the push rod associated therewith. Fig. 10 is a detail side view of a modified form of the rear end of the foot pedal lever and push rod associated therewith. Fig. 11 is a plan view of Fig. 10, as seen from the line XI—XI in Fig. 10. Fig. 12 is a side view of another modified form of the rear end of the foot pedal lever and push rod associated therewith. Fig. 13 is a plan view of Fig. 12, as seen from the line XIII—XIII in Fig. 12. Fig. 14 is a side view of another modified form of the rear end of the foot pedal lever and push rod associated therewith. Fig. 15 is a rear view of Fig. 14. Fig. 16 is a plan view of Fig. 14 as seen from the line XVI—XVI in Fig. 14. Fig. 17 is a side view of the lower end of the push rod. Fig. 18 is a side view of the lower end of the push rod, said push rod being turned a quarter turn from that shown in Fig. 17. Fig. 19 is a bottom plan view of Fig. 17. Fig. 20 is a detail plan view of the rear end of the foot pedal lever as employed in Figs. 10, 11, 12 and 13.

Fig. 21 is a sectional view through the cover cap and wall of the housing showing the locking mechanism between the cover plate and the housing. Fig. 22 is a side view of a portion of the cover element and the housing, showing the locking mechanism between these two elements. Figs. 23, 24 and 25 are perspective views showing several of many modified shapes of my sanitary container.

In the drawings is shown a housing element 10 having a cover element 11, having turned down edges to fit over the upper end of the housing 10. The top portion of the cover element is depressed or made in a funnel shape as illustrated at 12, and is provided with a hole 13 in 15 the central portion thereof. At 14 is a closure element for the hole 13 which is hinged at 15 to the cover element 12. At 16 is a depending element 16 which is integral with the element 14, which engages the L shaped portion 17 of the 20 push rod 18. At 19 is a rod carried in bearings 19' which are attached to opposite sides of the housing 10 by being welded thereto or by being otherwise suitably attached thereto, and on the rod 19 is mounted the foot pedal rod 20, the outer 25 end of which extends through a slot 21 in the lower portion of the housing 10 and on the outer end of the foot pedal rod 20 is a foot pedal 22, as shown in Figs. 1, 8 and 9, the inner end of the foot 30 pedal lever 20 is twisted and bent in a U shape 30 23, the upper portion of which is provided with a hole 24 and the lower portion of which is provided with a slot 25. Passing through the hole 24 is the lower end of the push rod 18, which is provided with a depending flattened portion 26, 35 which is adapted to engage in the slot 25 as a means of preventing the turning of the push rod 18. At 27 is a cotter pin which is passed through the lower end of the rod 18 as a means of preventing the rod 18 from being removed from 40 the hole 24. At 28 and 28' are outwardly projecting elements attached to opposite sides of the upper portion of the housing 10 and on which rests the flanges 29 of the container can 30, as a means of supporting the container can 30 in the 45 housing 10. The outwardly projecting element 28 is provided with a hole 31, through which the push rod 18 passes, the hole 31 functioning as a guide for the upper end of the push rod 18. The hinge element 15 is provided with a spring 50 32 which functions to cause the closure element 14 to stand in a closed position as shown in Figs. 1, 2 and 3.

In Fig. 7 is shown the same elements as shown in Fig. 6 except that weights 33 are attached to 55 the underside of the element 16 and function to close the cover element 14 by gravity instead of spring action as shown in Fig. 6.

It will be noticed that the L shaped portion 17 60 of the push rod 18 extends over the edge of the

5 container 30 to engage the element 16, therefore the container 30 could not be removed from the housing 10 without striking the L shaped portion 17 of the push rod 18 and in order to remove the container 30 it is necessary that the L shaped portion 17 be turned sideways as shown in Fig. 5. This is done by taking hold of the L shaped portion 17 and lifting it upward, thereby removing the portion 28 of the rod 18 from the slot 26 10 whereupon the L shaped portion 17 may be turned in the direction of the arrow A to the position shown in Fig. 5, at which time the container 30 may be lifted upward and removed from the housing 10. It will be understood that to perform the foregoing operation the cover 11-12 must be removed from the housing 10.

15 In using this container it is obvious that by placing the foot on the foot pedal 22 and pressing downward thereon, that the foot pedal lever 20 will take the position of the dotted line 29, thereby raising the push rod 18 and causing the element 14 to drop to the dotted position 14, at which time the opening 13 is open and objects may be dropped therethrough and into the container 30, and then by removing the foot from the pedal 22 the foot lever 20 will return to its original position and the element 14 will close the opening 13 by reason of the action of the spring 32 or the weights 33.

20 It will be noticed that in opening the element 14 there is an upward pressure from the push rod 18 and the L shaped portion 17 thereof against the element 16 which is attached to the cover portion of the housing 10 and this pressure might 25 tend to raise the cover portion 11-12 from the housing 10, therefore it is necessary to provide some means of holding the cover 11-12 on the housing 10. This is done by providing holes in the portion 11 of the cover and in the upper portion 30 of the housing 10 so that when the cover 11-12 is placed on the housing 10, the holes will register with each other.

35 At 34 are button like elements positioned in the holes just described, said button like elements 34 being mounted on spring leaves 35 the lower 40 end of which are rigidly attached by some suitable means such as welding or the like, to the upper portion of the housing 10 so that the buttons 34 may be pressed inwardly to release the element 11 so that the cover element 11-12 may 45 be removed from the housing 10.

50 As previously explained, it is necessary that the L shaped end 17 of the push rod 18 must be turned sideways in order to remove the container 30. I have shown several connections between the push rod 18 and the pedal lever 20 which will permit this operation. In Fig. 10 is 55 shown the pedal lever 20 having a twisted end 20' and as shown in Fig. 20, the twisted end is provided with two holes 36 and 37. The lower end of the push rod 18 as shown in Figs. 17, 18 and 19 is provided with flattened portions 38 and a downwardly extending pin portion 39, thereby providing shoulders 40 on the push rod 18.

55 In assembling the push rod 18 on the pedal lever portion 20, the pin portion 39 is passed through the hole 36 and the shoulders 40 rest on the portion 20' and the push rod 18 is held in this position by means of a cotter pin 41 which passes through a hole 42 in the pin portion 39. 60 At 43 is a U shaped spring element straddling the push rod 18 and bearing against the flattened sides 38 of the push rod 18, the ends of said

65 spring elements 43 being bent downwardly and passed through the hole 37 in the element 20' as shown in Figs. 10 and 11, the object of said spring element 43 being to hold the push rod 18 from rotating and to retain the L shaped portion 17 in the positions shown in Figs. 1 and 4, and in order to turn the L shaped portions 17 for the reasons previously described, all that is necessary to do is to take hold of it and turn it, and the spring 43 will yield to permit the turning of 10 the push rod 18. In Figs. 12 and 13 is shown in a construction similar to that shown in Figs. 10 and 11 except a flat spring 43' is substituted for the wire spring 43 and the ends of the spring 43' are wrapped around a pin 44 which is rigidly set 15 in the hole 37 of the element 20', and the function of the spring and the operation of turning the push rod 18 and the L shaped portion 17 is identical with that described for Figs. 10 and 11. In Figs. 14, 15 and 16 is shown another modification 20 of the connection between the push rod 18 and the pedal lever 20 in which the lower end of the push rod 18 is made the same as shown in Figs. 17, 18 and 19. The pedal lever rod 20 as shown in Figs. 14, 15 and 16 is left straight and a spring element 45 is riveted to the side of the lever 20 and a portion of the spring element 45 is bent in an L shape 45' and is provided with a hole to receive the pin 39 on the push rod 18 with the shoulders 40 resting on the portion 45' of the 25 spring 45. The spring 45 rests against one of the flat sides 38 of the push rod 18 and holds the other flat side 38 against the pedal lever 20. It will be understood that the hole through which the pin 39 passes, is elongated to permit the movement of the spring 45 when the push rod 18 is turned. 30

35 In view of the foregoing description, it is obvious that the container proper 30, may be removed from the housing 10 and sterilized if so desired and then replaced. This feature makes my sanitary container desirable for use in such places as 40 doctors' offices, dentists' offices and in such places where unsightly things such as bandages and the like are discarded. 45

Such modifications may be employed as lie 50 within the scope of the appended claims and having fully described my invention, what I claim as new and desire to secure by Letters Patent is—

1. In sanitary containers, the combination of 55 an outer stationary housing and an inner removable container supported on parts integral with said housing, a detachable cover element for said housing having a depressed funnel shaped section and a port at the center thereof and a closure element for said port hinged below the funnel shaped section of the cover; and a vertically positioned rod arranged intermediate the container and the housing, a pedal element arranged below the removable container and being pivotally 60 mounted within the housing; one end of said rod detachably engaging said closure element for actuating said closure element and the other end of said rod engaging the foot pedal element in such a manner that the rod may be revolved and 65 set at fixed positions.

2. In sanitary containers as in claim 1, and means for normally holding said closure element in a closed position under said port.

3. In sanitary containers as in claim 1, and 70 means for detachably securing said cover element on said housing.
